UNITED STATES PATENT OFFICE.

JAMES R. SMITH, OF MECHANICSVILLE, NEW YORK.

PIPE AND TUBE CUTTER.

1,112,728.

Specification of Letters Patent.

Patented Oct. 6, 1914.

Application filed September 2, 1913. Serial No. 787,678.

To all whom it may concern:

Be it known that I, JAMES R. SMITH, a citizen of the United States, residing at Mechanicsville, county of Saratoga, and State 5 of New York, have invented certain new and useful Improvements in Pipe and Tube Cutters, of which the following is a specification.

This invention relates to pipe and tube 10 cutters.

The invention has for its objects, first, the provision of a pipe and tube cutter having an improved automatic feeding means, whereby, as the tool is operated, successively 15 deeper cuts are made; second, an improved hand feeding means whereby the cutters may be initially adjusted or adjusted while the cutting operation is progressing; third, a novel combination of improved hand and 20 automatic feeding means either of which may be used; fourth, improved means for cushioning the tension of the cutters on the pipe or tube to compensate for any irregularities of the latter during the cutting operation; fifth, improved reversible pawls for 25 the pawl and ratchet feeding means, whereby the parts may be arranged in feeding or non-feeding relation or in neutral position or so that either a right or a left turn may 30 be utilized in operating the tool.

An embodiment of the invention adapted to carry out the foregoing objects and illustrating the mode of operation of the invention is set forth hereinafter, but is to be 35 considered as illustrative, rather than restrictive, of the scope of the invention, as modifications may be resorted to.

In the accompanying drawings: Figure 1 is a perspective of the invention applied to 40 a pipe or tube; Fig. 2, a longitudinal section with the chain of cutters broken away; Fig. 3, a cross section on line 3—3, Fig. 2; and Fig. 4, a cross section on line 4—4, Fig. 2.

The cutter block or head 1 is closed at one 45 end 2 and provided with a removable, suitably secured, plate 3 at its opposite end. This block or head has parallel lower sides 4 and is open at its bottom. At one end the head is provided with ears 5 which have 50 curved channels 6 on their inner faces. Ears 7 rise from the cutter block or head 1. An operating lever 8 is provided with an ear 9 which has trunnions 10 that are pivoted in the ears 7, said ear 9 lying between ears 7. 55 Opposite ends of this lever are internally threaded to receive operating handles 11,

whereby the entire cutter is operated in making the cut in the tube or pipe and, if desired, is utilized to automatically feed the cutting means to make successively deeper 60 cuts, as will appear presently.

Journalized in the ends 2 and 3 is a feed screw 12 to which is secured or keyed a hand wheel 13, whereby the screw may be turned by hand to effect a hand adjustment 65 of the cutting means.

Screwed on the opposite end of the feed screw 12 is a nut 14. Loose on a blank portion 15 of the feed screw is a ball bearing 16. Interposed between the ball bearing 70 and the nut 14 is a relatively heavy coil spring 17 which acts as a cushion for the tension of the chain of cutters so that if any irregularity on the tube or pipe is encountered by a cutter, said spring will yield and 75 prevent any breakage of the parts or the throwing of the cutters out of the desired plane of operation or out of the cut.

An internally screw-threaded wheel block 18 is engaged with the feed screw and slides 80 within the cutter block or head 1 in one direction or the other according to how said feed screw may be revolved. The wheel block has a neck portion 19 which engages the parallel lower side 4 and is thus guided 85 in its movements when being fed by the screw. The lower part of the cutter block is bifurcated and in said bifurcation is located the cutter 20 which is carried by pin 21, the latter passing through the wheel 90 block and being connected to the links 22. The remaining cutter mechanism consists of a chain of links like the links 22 and cutters 23 like the cutter 20, certain of the pins 24 which form the joints for the links and 95 the journals for the cutters, projecting so that any of them may be entered in the grooves 6 of the ears 5 to take up or let out the chain of cutters to any desired extent after they have been applied to the pipe or 100 tube and preliminary to a rough adjustment which may be obtained by turning the hand wheel 13.

Loosely splined at 25 to the feed screw 12 is a ratchet wheel 26 which affords means 105 for turning the feed screw without interfering with the slippage therethrough of the latter. The ratchet wheel is loosely incased in an operating head 27 which has aligned slots 28 in opposite faces thereof through 110 which the screw 12 loosely passes. The operating head is pivoted at 29 to the operat-

ing lever 8, whereby any rocking or movement of said lever causes a corresponding movement of the operating head. Interposed between the hand wheel 13 and the operating head is a spring 30 and a cup washer 31, the latter bearing against the head 27, the function of which, in connection with the pivotal connection 29, is to afford sufficient play or looseness to the head 27 to compensate for the rocking movements of the lever 8 and for any longitudinal movement of the feed screw 12 caused by the actuating action of the spring 17.

The operating head 27 is provided with bearings 32 which receive pawls 33. Preferably these bearings and the pawls are cylindrical, the pawls being provided with inclined faces 34 and relatively sharp edges 35. The heads of the pawls have crossed or intersecting grooves 36. The arrangement of the pawls is such that they may be turned either 90° or 180° to bring the sharp teeth 35 in the plane of the ratchet wheel, which is the neutral position and leaves the ratchet wheel free, or, to dispose the said teeth crosswise of the ratchet wheel so that they will engage the teeth of the latter, such arrangement of the pawls being as shown in Fig. 4, where the ratchet wheel may revolve in a clockwise direction, or, the pawls may be completely reversed from the position shown in Fig. 4 so that the ratchet wheel may revolve in a counter-clockwise direction. Thus, the cutter may be operated either right or left or the automatic operating mechanism be rendered ineffective and neutral, permitting the feed screw 12 to be turned only by the hand wheel 13.

To lock the pawls in whatever position they may be set, I provide latches 37 pivoted to the head 27 at 38 and connected by a coil spring 39. The ends of the latches can be raised and the pawls set, as desired, and said ends then allowed to fall into the groove 36 which is in line therewith. I am aware that other means could be provided for spring actuating the pawls and for preventing them from turning and I do not limit myself to the precise retaining means disclosed.

To apply the cutter to a pipe or tube, a section of which is shown at 40 in Fig. 1, the chain of cutters is disconnected from the ears 5 and passed around the pipe or tube 55 and the pins 24 engaged in the recesses or grooves 6, giving a preliminary adjustment of the cutters. The hand wheel 13 may now be turned to rotate the feed screw 12 and adjust the wheel block to bring the cutters 20, 23, against the pipe or tube 40. The handles 11 are then grasped and the entire tool rocked on the pipe or tube. During this rocking movement, the lever 8 turns with the trunnions 10 and the operating head 27 is shifted in relation to the ratchet wheel,

such motion being transmitted through one of the pawls to the ratchet wheel and through the ratchet wheel to the feed screw 12, which by turning, feeds the wheel block 18 lengthwise of the cutter block 1. Consequently a successively deeper cut is made in the pipe or tube 40. If the automatic feed is not desired, the pawls are placed in the neutral position and hence the rocking of the lever 8 does not turn the ratchet wheel. The feed of the cutters, in deepening the cut, may then be effected by turning the hand wheel 13. If the cutters encounter any irregularity in the pipe or tube, the jar is cushioned by the spring 17, the feed screw 80 meanwhile shifting longitudinally.

The adjustability of the wheel block 18 does not disturb the regularity of the circular arrangement of the cutters 23 when they are engaged with the pipe or tube, inasmuch as said block 18 carries the cutter 20 which also bears on the pipe or tube. Furthermore, the cutting system, being articulated, automatically adjusts itself to the pipe or tube once the chain has been applied thereto. The adjustability of the chain of cutters permits use on pipes or tubes of various diameters.

Having thus described my invention, what I claim as new and desire to secure by Letters Patent, is:—

1. In a pipe and tube cutter, the combination with a cutter head, of a bodily and longitudinally shiftable feed screw carried thereby, cutters having a screw-threaded block engaged by the feed screw, and a cushion coöperating with the feed screw.

2. In a pipe and tube cutter, the combination with a cutter head, of a bodily and longitudinally shiftable feed screw carried thereby, a block having screw-threads 105 engaged by the feed screw and guided by said head, said block being adapted for adjustment by said feed screw, means for turning the feed screw, a cushion coöperating with said feed screw, and a chain 110 of cutters connected to the block and to the head.

3. In a pipe and tube cutter, the combination of a cutter head which is bodily shiftable as an entirety, a cutting device 115 bodily shiftable with said cutter head, adjusting means coöperating with the cutting device for causing it to make successively deeper cuts, and operating means common to the head and cutting device adapted for both bodily shifting the said head and adjusting the cutting device.

4. In a pipe and tube cutter, the combination with a cutter head, of a cutting device, said cutter head and cutting device 125 being bodily shiftable together as an entirety, adjusting means on the head for adjusting said cutting device, means for bodily turning said cutter head, selective means operated by said turning means 130

adapted, when set for use, to automatically operate said adjusting means, whereby the cutting device is caused to make successively deeper cuts as the cutter head is turned, and 5 means for manually operating said adjusting means independently of the aforesaid automatic operation thereof by the manipulating means.

5. In a pipe and tube cutter, the combination with a movable cutter head, of a cutting device carried thereby, said cutter head and cutting device being bodily shiftable together as an entirety, adjusting means on the head for adjusting said cutting device, 10 a rockable lever mounted on the bodily shiftable cutter head adapted for shifting said head and cutting device as an entirety, and means operated by said rockable lever cooperating with said adjusting means where- 15 20 by the cutting device is automatically caused to make successively deeper cuts when the lever is rocked.

6. In a pipe and tube cutter, the combination with a movable cutter head, of a cutting device carried thereby, said cutter head and cutting device being bodily shiftable together as an entirety, adjusting means on the head for adjusting said cutting device, a rockable lever mounted on the movable 25 30 cutter head, and pawl and ratchet mechanism operated by said lever and adapted to operate the adjusting means aforesaid, said lever being employed both for turning the movable cutter head and for automatically 35 adjusting said cutting device when the cutter head and cutting device are bodily shifted.

7. In a pipe and tube cutter, the combination with a cutter head and a cutting device carried thereby, said head and cutting 40 45 device being bodily shiftable together as an entirety carried by the head which is adapted for adjusting the cutting device, a ratchet wheel for turning said screw, movable operating means carried by the cutter head adapted for turning said head, and

pawl mechanism operated by said operating means adapted for coöperation with said ratchet wheel when the cutter head and cutting device are bodily shifted.

8. In a pipe and tube cutter, the combination with a cutter head, of a chain of cutters, a feed screw carried by the head which is adapted for adjusting the chain of cutters, a ratchet wheel for turning said screw, a rockable lever carried by said head, an operating head pivotally connected to the lever, and pawls carried by said head adapted to coöperate with said ratchet wheel.

9. In a pipe and tube cutter, the combination with a cutter head, of a longitudinally shiftable feed screw carried thereby, a chain of cutters adapted for adjustment by the feed screw, a cushion coöperating with the feed screw, a ratchet wheel splined to 60 65 said feed screw, a manipulating device carried by the cutter head, an operating head connected to the manipulating device, and pawl mechanism carried by the operating head and coöperating with the ratchet wheel. 70

10. In a pipe and tube cutter, the combination with a cutter head, of a cutter, means for adjusting the cutter, a ratchet wheel for operating said adjusting means, a movable manipulating device carried by the cutter 75 head, an operating head connected to said manipulating device, and settable pawls carried by said operating head and adapted to engage the ratchet wheel, said pawls being adapted to be arranged or set to permit 80 free turning of the ratchet wheel in either direction or entire freedom of said ratchet wheel.

In testimony whereof, I hereunto affix my signature in presence of two witnesses.
